H. A. BURNES

TUBE FRAME

Filed March 4, 1922

UNITED STATES PATENT OFFICE.

HENRY A. BURNES, OF BOSTON, MASSACHUSETTS, ASSIGNOR TO SHAWMUT ENGINEERING COMPANY, OF BOSTON, MASSACHUSETTS, A CORPORATION OF MASSACHUSETTS.

TUBE FRAME.

Application filed March 4, 1922. Serial No. 541,101.

To all whom it may concern:

Be it known that I, HENRY A. BURNES, a citizen of the United States, and resident of Boston, in the county of Suffolk and 5 State of Massachusetts, have invented certain new and useful Improvements in Tube Frames, of which the following is a specification.

This invention relates to the art of weaving and is especially concerned with the improvement of tube frames which are used in weaving pile fabrics, particularly carpets, for the purpose of delivering to the fabric being woven the tufts of yarn that form 15 the pile.

This application is a substitute for the application on precisely the same invention filed by me in the United States Patent Office June 1, 1915, Serial No. 31351 which was 20 allowed, subsequently renewed and again allowed and subsequently forfeited, said renewed application filed April 19, 1916, No. 92,313.

Much difficulty and trouble is experienced 25 in the practical use of these tube frames owing to imperfect alignment and positioning of the tubes and even when the tubes are correctly positioned at the outset they are subject to displacement, distortion and 30 breakage under the stress of practical use.

The present invention is intended to provide a tube frame construction which will ensure perfect spacing and positioning of the individual tuft tubes and afford reliable and 35 simple means for holding and effectively supporting them against accidental displacement. This principle of construction also renders it practical and convenient for the attendant to quickly replace any tube that 40 may become bent or broken without material loss of time or even removing the tube frame from the loom.

A further advantage to be derived from the construction and arrangement comprising 45 the present invention is that of protecting the yarn comprising each tuft element from chafing against the sharp end edge at the entering end of its appropriate guide tube since the tube-retaining member disposed at the intake ends of the tubes acts as a guard or protecting ledge preventing the 50 yarn from rubbing against the sharp edge of the tube.

To this end the invention comprises a tube

frame embracing a longitudinal carrier to 55 which a series of properly spaced tuft tubes are secured in parallelism with one another, and so supported as to both protect them against displacement strain, and permit the quick removal of any injured tube and the 60 substitution of a new tube without appreciable loss of time by the operator without the aid of the repair mechanic.

This and other features of the invention 65 will be described in the following specification and will be defined in the claims hereto annexed.

In the accompanying drawings I have illustrated a simple and convenient embodiment of the principles of this invention in 70 which:

Figure 1 is a plan view of the carrier bar element of the tube frame.

Figure 2 is a front elevation of the tube frame with its end supporting members for 75 linking it to the supporting chains.

Figure 3 is an end elevation of the tube frame.

Figure 3^a is a transverse section on the line 3—3 of Fig. 1 with one of the tube-engaging members shown in Figure 3 omitted.

Figure 4 is a similar transverse section with the reinforcing tube-engaging member omitted.

Figure 5 is a perspective view showing a portion of the carrier bar in dotted lines with the tube-engaging members arranged in operative position for service.

Figure 6 shows the form of the blank from 90 which the individual tubes are made.

Figures 7, 8, 9 and 10 are various detail views illustrating the construction of the preferred form of tube.

Figures 11 and 12 are cross-sectional views 95 of one of the tuft tubes on the planes indicated respectively by lines 11—11 and 12—12 on Figure 9.

The main elements in this tube frame construction, according to the principles of the 100 present invention, consist of the longitudinal carrier bar 12 which forms, so to speak, the back-bone of the tube frame and is provided at each end by suitable brackets 13 by which it is connected with and supported by the chains or moving elements by which the tube frame is carried into and out of operative position to deliver the yarn tufts to the 105

interstitial spaces between the warp elements so as to form the pile of the fabric being woven.

To this longitudinal carrier bar are secured a series of tuft tubes or tubular guides through which the tufts of yarn are properly fed to the fabric as desired.

The problem with which this invention deals is that of positioning or spacing and anchoring the individual tubes to the bar in such a way that the likelihood of their displacement from proper position shall be minimized, while at the same time making it possible for the attendant to easily and quickly substitute a new tube whenever one is bent or broken and that without the need of special appliances or tools.

I will first describe the preferred construction of tube although it will be understood that the invention is not limited to the particular form and construction of tube herein disclosed.

In Figure 6 I have shown the form of the blank preferably made of thin sheet metal from which the complete one piece tube is formed. As will be seen the head or intake end of the tube is made wider than the body portion which is to form the guiding tube itself and at the juncture of the head and body portion the blank is provided with aligned slits 18. The form of blank shown is first bent or folded on the middle line α so as to bring the sides 19 into nearly parallel relationship, and the edge portions of each side are then folded in the manner best shown in Figure 11 to overlap one another thereby forming a flat tubular member of approximately triangular or V shape in cross section. The extreme edge portions of the sides of the head portion are folded along the dotted lines α to form lips 21 which abut against each other in the same plane as shown in Figures 7 and 12, the head portions themselves being given, on the plane 12-12, a U-shaped arch formed with its rear face flat to lie snugly against one side of the carrier bar 12. With this construction the tubular portion tapers inwardly toward its delivery end to make a narrow flat tuft container whose delivery end is formed to pass readily between the warp elements of the fabric in the loom.

It will be seen that forming the tube in this way from the blank described leaves the rear of the head of the tube offset with relation to the overlapped flanges 20 of the guide portion of the tube.

The preferred means for detachably securing the tubes to the carrier bar in proper spaced relationship is shown in Figures 3 and 5. In this case, on the upper face of the carrier bar is secured a guide member or plate 27 formed with a projecting flange 28 provided with parallel guide slots 29 adapted to engage the individual tubes at a

point approximately midway of the ends of the tube and thereby accurately space them from one another beside affording a strong reinforcement to hold the tubes against accidental displacement from their proper alignment and operative positions. As the tubes are tapered these slots when made of a size and shape to correspond with the engaged portion of the tube serve to limit the endwise movement of the tubes in the direction of their delivery end.

To cooperate with the reinforcing and spacing member 28 in holding the tubes firmly in position I sometimes employ an additional tube engaging member shown in this case as comprising a plate 14 detachably secured to the carrier bar 12 into whose edge portion a series of notches are cut to leave tongues or projections 16 of a width to enter the end portion of the head of the tube so as to engage the inturned abutting flanges 21 and hold them against the carrier bar and also against lateral and twisting movement. The tongues or projections 16 are sufficiently flexible to allow the operator to bend out any individual tongue to permit disengagement of its interlocked tongue for the purpose of withdrawal or replacement. When disengaged from its interlocked tongue the tube may be drawn endwise out of the positioning member 28.

The tongues or clamping members 16 are too thin to impede or interfere with the threading of the tuft yarns.

To still further strengthen the locking engagement between the carrier bar and the individual tubes I may use a supplemental clamping bar 25 notched to form short tongues 26 arranged to project into the end of the head portion of the tube where it joins the tubular body portion, said supplemental clamping bar being secured to the carrier bar in any convenient manner.

If preferred this supplemental clamping bar 25 may even be substituted entirely for the reinforcing spacing bar since its tongues are made of a width to fit inside the head end of the tube and thus form a spacing and positioning member as well as a tube locking and engaging member. However, a spacing member like the plate 28 which engages the sides of the tubular body of the tube has the advantage of affording a more complete support and reinforcement for the tubes against displacement or bending, while leaving ample sufficient length of tube projecting beyond to form so to speak, a hollow needle for passing the tuft yarns between the warp elements in the reeding operation.

It will be seen that either slotted bar 14 or 28 affords a reliable spacing or positioning member by which the uniform and correct spacing of the tuft tubes is effected with the side walls of adjacent tuft tubes at their rear or intake ends in supporting contact

one with another. While it is preferred that either or both of such spacing and positioning members should be detachable for convenience it will be clear that either of them will properly perform its function whether integrally or permanently united with the carrier or detachably connected therewith.

It will also be seen that the yarn is protected from catching or chafing as it enters the individual tuft tubes by reason of the adjacent longitudinal retaining strip forming a protective ledge preventing contact with the sharp end edge of each tube.

15 Furthermore the tube-supporting or retaining strip forming as it does a common medium for securing a series of tubes to the carrier bar makes possible, among other advantages, the quick removal of one set of tubes and its replacement by another, while the arrangement is such that the removable fastening devices, in this case shown as screws, do not penetrate any of the tubes themselves. The separate detachable protective strip makes possible the renewal or replacement without disturbing the tubes or any other part of the structure since it can be removed and replaced while the yarn remains in the tuft tubes.

30 What I claim is:

1. A tube frame for weaving embracing in its construction a longitudinal carrier bar, a series of tuft tubes held rigidly but detachably to said bar in operative relationship, a tube supporting member extended from the bar to engage the middle portions of the tubes and a clamping member mounted on the bar to detachably engage the intake ends of said tubes and thereby cooperate with the said supporting member in correctly positioning and holding the tubes in place, substantially as described.

2. A tube frame for weaving embracing in its construction, a longitudinal carrier bar, a series of tuft tubes held against an exterior face of the bar and extending in parallelism with one another beyond said bar, a supporting member extending beyond said face of the bar to engage and hold the intermediate portions of the tubes in order to maintain them in operative position, and a tube locking member mounted on the bar in position to detachably engage and hold the intake portions of the tubes, substantially as described.

3. A tube frame for weaving embracing in its construction a longitudinal carrier bar, a series of tuft tubes aligned in parallelism with one another along one side of said bar, means for securing said tubes in their aligned position comprising a holding member projecting from the bar in position to detachably engage the tuft tubes intermediate of their intake and outlet ends to support the tubes against movement in one

direction, and a cooperating holding member arranged to engage the intake ends of the tubes and hold them against movement in the reverse direction, substantially as described.

4. A tube frame for weaving embracing in its construction a carrier bar, a series of tuft tubes mounted in parallelism with one another along one side of the bar, tube engaging means arranged along one portion of the bar to hold the tubes against movement in one direction and cooperating tube engaging means arranged along another portion of the bar to engage the intake ends of the tubes to hold them against movement in the opposite direction, said latter engaging means having releasable engagement with the tubes to permit the removal and replacement of any of the tubes, substantially as described.

5. A tube frame embracing in its construction a longitudinal carrier bar, a slotted spacing plate secured thereto with its slotted portion projecting beyond one side of the bar, a series of tuft tubes arranged in parallelism with one another along one side of the bar and having their tubular yarn guiding portions extending through said slots for support, tube clamping means secured to the bar in position to engage the intake ends of the tubes and hold the tubes firmly but detachably within their respective slots, substantially as described.

6. A tube frame embracing in its construction a carrier bar, a series of tuft tubes arranged in parallelism along one side of the bar, oppositely disposed holding members for engaging and detachably holding said tube in position on said bar, one of said members being made of flexible material to permit disengagement and removal of the tubes, substantially as described.

7. A tube frame embracing in its construction a longitudinal carrier, transversely disposed tuft tubes arranged along said carrier bar in parallelism with one another with their delivery ends spaced apart, means for engaging said tuft tubes intermediate of their ends to support them on the bar, cooperating holding means for detachably securing the intake ends of said tubes to the carrier bar, said cooperating holding means embracing a longitudinal member provided with a series of projecting tongues disposed to anchor the intake ends of the tube to the carrier bar, substantially as described.

8. In a tube frame for weaving, the combination of a longitudinal carrier bar, a longitudinal tube-holding and spacing member projecting laterally from the bar and a series of tuft guiding tubes inserted in said holding member transversely thereof and securely held to the bar in parallel spaced relationship, substantially as described.

9. A tube frame embracing in its con-

70

struction a carrier bar, a series of tuft tubes comprising tubular body portions and intake or head portions offset with relation to the tubular body portion, oppositely disposed 5 clamping members arranged to form holding engagement with the opposite end edges of said offset head portion, and a reenforcing or spacing member provided with slots to engage and support the body portions of 10 said tubes, substantially as described.

10. A stamped metal tuft tube for a tube frame embracing in its construction, a flattened tapered tubular portion and a relatively larger intake head portion offset at the 15 rear beyond the rear wall of the tubular portion to form a transverse ledge, substantially as described.

11. A stamped metal tuft tube for a tube frame embracing in its construction a tubular portion of approximately V-shape in cross section whose sides are inwardly turned to overlap and form the rear wall, and a head portion whose sides are turned inward to leave their edges abutting against 20 each other to form a flat rear wall adapted to lie against the exterior face of a carrier member, said flat rear wall being offset with relation to the rear wall of the tubular portion, substantially as described.

12. A stamped metal tuft tube for a tube frame embracing in its construction a tubular body portion for guiding the tuft yarn to the work, and a relatively larger head portion whose rear wall is offset beyond the 35 rear of the tubular portion thereby leaving the head portion with exposed edges at its upper and lower ends, substantially as described.

13. A stamped metal tuft tube for a tube frame embracing in its construction a tubular body portion for guiding the tuft yarn to the work and a head portion offset at its rear beyond the rear wall of the body portion 40 to leave an opening at the shoulder forming the offset so that the head portion at its rear is open at both ends, substantially as described.

14. In a tube frame the combination of a longitudinal carrier bar, a tube holding 45 member extending lengthwise of the bar and projecting laterally therefrom and provided with a series of closely arranged parallel tube encircling slots formed to surround the middle portion of the tubular part of the 55 tuft tube to position the individual tubes and to support them against transverse strains on all sides, and against endwise movement in one direction and cooperating holding means disposed to detachably engage the tubes nearer their intake ends, substantially 60 as described.

15. In a tube frame the combination of a longitudinal carrier bar, a tube holding and spacing member extending longitudinally 65 along said bar and projecting laterally

therefrom to form a tube supporting ledge said ledge being provided with tube receiving and holding openings in which the tuft tubes are inserted, and detachably locked, substantially as described. 70

16. A tube frame embracing in its construction a longitudinal carrier bar, a series of parallel transversely projecting tuft tubes arranged side by side, and rigidly secured to said carrier bar, said carrier bar being provided with an exterior longitudinally extending tube-spacing member that is transversely slotted to form holding and spacing engagement with the individual tuft tubes whereby the individual tubes are correctly positioned when attached to said carrier, substantially as described. 80

17. In a tube frame for pile fabric weaving, the combination of a longitudinal carrier bar provided with a longitudinally extending tube-positioning member transversely slotted to form intervening holding fingers adapted to overlap the rear or intake ends of the individual tuft tubes, and a series 90 of separate tuft tubes arranged side by side with their side walls engaged in the respective slots, whereby the tuft tubes are held in correctly spaced relationship on the carrier bar, substantially as described.

18. In a tube frame for pile fabric weaving, the combination of a longitudinal carrier bar, a series of transversely disposed tuft tubes arranged in parallelism on the outside of said bar with the side walls of adjacent tubes in supporting contact with each other and an external positioning and holding member extending longitudinally of said bar and overlapping the rear or intake ends of the individual tuft tubes to insure correct positioning of said tubes when attached to the carrier, substantially as described. 100

19. In a tube frame for weaving, the combination of a longitudinal carrier bar, an exterior tube-supporting and attaching member extending lengthwise of the bar and a series of tuft guiding tubes detachably secured to said attaching member to permit quick removal and insertion of the tubes, substantially as described. 110

20. In a tube frame for pile fabric weaving, the combination of a longitudinal carrier bar, a series of transversely disposed tuft tubes arranged in parallelism along the outside of said bar, and an external spacing and positioning member extending longitudinally of said bar in position to receive the relatively narrow intermediate portion of said tuft-tubes while allowing the wider rear ends thereof to lie in supporting contact with one another, substantially as described. 120

21. In a tube frame for pile fabric weaving, the combination of a longitudinal carrier bar, a series of transversely disposed tuft tubes arranged in parallelism along one 125

side of the bar with their side walls in supporting contact near their rear or intake ends, an external retaining and spacing member formed with a series of parallel 5 spacing slots arranged to engage the tubes individually and correctly position them on the bar, substantially as described.

22. In a tube frame for pile fabric weaving, the combination with a longitudinal carrier bar and its series of parallel transversely disposed tuft tubes, of a longitudinally extending strip constructed and arranged to form a protective ledge to prevent the yarn from chafing against the rear ends of the 10 tuft tubes, said protective strip also affording means for removably securing the tuft tubes to the carrier bar.

23. A tube holding member for attaching tuft guiding tubes to the carrier bar of a 15 tube frame, comprising a longitudinal hold-

ing member adapted to be rigidly secured to the carrier bar and formed to afford lateral supporting engagement with the individual tuft tubes to space and retain them in operative relationship, substantially as de- 25 scribed.

24. In a tube frame for weaving, the combination of a longitudinal carrier bar tube-spacing and holding means forming a ledge extending exteriorly of the bar in a longitudinal direction and provided with transverse recesses, and a plurality of parallel tuft tubes inserted in said recesses for support, said inserted tubes being firmly but releasably held in parallel relationship, sub- 30 35 stantially as described.

In witness whereof, I have subscribed the above specification.

HENRY A. BURNES.
